UNITED STATES PATENT OFFICE.

WILLIAM B. HUGHES, OF PHILADELPHIA, PENNSYLVANIA.

BILLET-MAKING MACHINE.

SPECIFICATION forming part of Letters Patent No. 674,769, dated May 21, 1901.

Application filed December 5, 1900. Serial No. 38,833. (No model.)

To all whom it may concern:

Be it known that I, WILLIAM B. HUGHES, a citizen of the United States, residing in Philadelphia, Pennsylvania, have invented 5 certain Improvements in Billet-Making Machines, of which the following is a specification.

One object of my invention is to quickly and economically convert a metal ingot into 10 a number of compressed billets, a further object being to provide mechanism whereby successive billet-blanks can be sheared from the ingot. These objects I attain in the manner hereinafter set forth, reference being had to 15 the accompanying drawings, in which—

Figure 1 is a vertical section of a billet-making machine constructed in accordance with my invention. Fig. 2 is a view of the same, partly in transverse section and partly 20 in elevation. Fig. 3 is a plan view, partly in section. Fig. 4 is a side elevation of part of the machine. Figs. 5 and 6 are sectional views illustrating the operation of the machine, and Figs. 7 and 8 are similar views 25 illustrating a modification of the invention.

In making billets from steel ingots it is the customary practice to first roll the ingot in a special blooming-mill and then to cut the rolled product into pieces of the proper size 30 for the billets, although in some cases the metal is poured into ingot-molds of small size, each producing an ingot of the proper size for a billet. Both of these plans are expensive, the first because of the special rolling-mill required and the labor necessary to reduce the 35 ingot to billet form, while the second plan requires the use of a great number of small molds and corresponding expenditure of time and labor in filling, handling, and discharging 40 the same. These objections I overcome by casting the ingot in a large mold in the usual way and as soon as said ingot has become sufficiently cooled to cause it to retain 45 its form cutting the same into billet-blanks and simultaneously compressing these blanks to form the billets, an operation which can 50 be readily performed, owing to the plastic condition of the metal, and which results in the production of properly-shaped billets of homogeneous metal, "piping" being prevent-

ed by reason of the pressure to which the plastic or semifluid mass has been subjected.

The machine for making billets in accordance with my invention consists of a substantial framework 1, having at one end a heavy 55 thrust-block 2 and at the other end a cylinder 3, with plunger 4, the latter having a head 5 with right-angled die-block 6, adapted to coöperate with a reverse right-angled die-block 7, secured to the thrust-block 2, as 60 shown in Fig. 1. Hence when the plunger 4 is projected by means of hydraulic or other pressure admitted to the cylinder 3 the dies 6 and 7 will inclose a space of the cross-sectional dimensions of the desired billet. 65

Upon the framework 1 are rails for the wheels of a truck 8, which is adapted for the support of an ingot-mold 9 and has suitable ways for the guidance of a slide-block 10, whereby the bottom of said ingot-mold may 70 be closed or opened. Movement of the slide-block 10 may be effected in any desired way, the means shown in the present instance for accomplishing this result comprising a power-cylinder 11, mounted on the main frame of 75 the machine and having a piston-rod 12, with cross-head connected by links 13 to bell-crank levers 14, mounted in bearings on the block 2, a link 15 and detachable pin 16 serving to connect each lever to projecting ears 17 on 80 the sliding block 10 when the ingot-mold truck has been moved into proper position on the frame of the machine.

Guide-flanges 18 on the top of the frame 1 serve to guide downward, close to the face of 85 the block 2, an ingot descending from the mold 9, and arms 19 on a transverse rock-shaft 20 on said frame 1 serve to press the lower portion of this ingot into close contact with the face of said block 2, the rock-shaft 90 20 being vibrated, so as to cause the arms 19 to subject the ingot to pressure or relieve it therefrom by means of power-cylinders 21 on the outside of the frame, the piston operated by these power-cylinders engaging with 95 an arm 22 on one end of the rock-shaft 20.

At one side of the frame 1 is mounted a power-cylinder 23, with piston-rod 24 in line with the opening formed by the die-blocks 6 and 7, and at the other side of said frame is a 100

roller-table 25 or other suitable form of power conveyer for carrying the billets away from the machine.

The head 5 of the plunger 4 is connected by rods 26 to a cross-head 27, which is connected to the plunger 28 of a supplementary power-cylinder 29 at the back end of the cylinder 3, constant pressure being maintained in this supplementary cylinder, so as to retract the plunger 4 and its head 5 when pressure is removed from the cylinder 3, or pressure may be admitted to the cylinder 29 when the cylinder 3 is opened to the exhaust, or vice versa.

15 The bottom of the mold 9 is normally closed by the slide-block 10 and the molten metal is permitted to remain in the mold until sufficiently cooled to cause the ingot to retain its form, whereupon the truck carrying the mold 20 is moved into position over the machine, the block 10 is coupled to the links 15, and the power is admitted to the cylinder 11, so as to operate the levers 14 and withdraw the block 10 from the bottom of the mold. The plunger 25 in the cylinder 3 being retracted, the ingot falls from the mold 9 down between the guide-flanges 18 and onto the die-block 6, as shown in Fig. 5, the arms 19 of the rock-shaft 20 pressing the ingot against the face of the 30 thrust-block 2. The plunger 4 is now projected so that the die-block 6 shears off the lower end of the ingot and presses this cut-off portion forwardly against the die 7, thereby compressing the plastic mass of metal between the two dies and imparting to it the 35 form desired for the finished billet, as shown in Fig. 6. This compression of the plastic mass solidifies the same and renders the billet homogeneous throughout, so that the finished billet is similar to one produced in the 40 ordinary way from fluid-compressed steel. As soon as the pressure upon the billet is relieved on the retraction of the die 6 the piston 24 of the power-cylinder 23 is projected 45 so as to thrust the billet onto the conveyer-table 25, by which it is carried away from the machine. As soon as the plunger 4 has been retracted the ingot again drops into position 50 on the die 6 and the operations before described are repeated.

The presser-arms 19 on the rock-shaft 20 serve to insure the vertical descent of the ingot and prevent any overturning of the same when it has been reduced in length, so that 55 only a small section remains. Hence the entire length of the ingot is fed to the die 6 and the shearing and compressing operations proceed until the ingot is entirely consumed.

By preference the ingot-mold is of greater 60 lateral dimensions at the center than at the ends; the shape of the ingot being that represented in cross-section in Fig. 3, so that the pressure of the dies 6 and 7 is exerted upon the blank sheared from the ingot, first at the 65 longitudinal center of the same and thence

progressively toward each end, whereby the flow of metal is from the center outwardly toward each end, the desired solidity of the billet from end to end being thus insured.

If desired, the compression of the billet 70 may precede the shearing of the same from the ingot. Thus in the modification shown in Figs. 7 and 8 the compression of the ingot is effected between the vertical face of a die-block 6^a and the opposing vertical face of a die-block 7^a, as shown in Fig. 7, the compressed portion of the ingot falling onto a projecting portion of the die 6^a when the latter is retracted, as shown in Fig. 8, and being sheared from the body of the ingot on the next forward movement of the plunger 5, at which time the compression of the next succeeding portion of the ingot is also being effected. The compressing-dies may, if desired, be independent of the shearing-dies, although for 80 purposes of economy and compact arrangement it is preferable to use the combined compressing and shearing dies, as shown, and certain features of the invention may also be embodied in a machine intended simply for 85 shearing the billet-blanks from the ingot without compressing them, or, on the other hand, the compressing-dies may be such as to convert the sheared-off section of the ingot into "shapes" instead of simple billets, thereby 90 dispensing with one or more of the rolling operations now necessary in converting a billet into "beams" or shapes and the like, the term "billet" as used in the claims being intended to cover such shapes as well. 95

The dies and adjacent parts of the machine may be hollow and water-cooled, if desired, and the relation of the parts of the machine may be changed without materially affecting the operation of the same. For instance, the 105 machine may be turned upon its side, the ingot-mold being supported in a horizontal position, and the billet may be delivered from the machine by gravity, the ejector-cylinder 23 and its piston-rod 24 in this case being so 110 disposed as to force the ingot from the mold and into the machine.

Having thus described my invention, I claim and desire to secure by Letters Patent—

1. The combination, in a billet-forming machine, of shearing-dies, means for feeding an ingot thereto, a presser for holding the ingot in proper alinement while it is being fed to the dies, and fluid-pressure devices for 120 acting on said presser, substantially as specified.

2. The combination, in a billet-forming machine, of shearing-dies, means for feeding an ingot thereto, so as to form successive 125 billets, and a billet-ejector operating transversely to the direction of movement of the dies, substantially as specified.

3. The combination, in a billet-forming machine, of shearing-dies, an ingot-mold car- 130

rier mounted so as to move the mold into position to feed the ingot to said dies, and a sliding block for closing the delivery end of the mold, substantially as specified.

5 4. The combination, in a billet-forming machine, of shearing-dies, and an ingot-mold carrier mounted so as to move the mold into position to feed the ingot to said dies, said carrier having a sliding block for closing the

delivery end of the mold, substantially as to specified.

In testimony whereof I have signed my name to this specification in the presence of two subscribing witnesses.

WILLIAM B. HUGHES.
